UNITED STATES PATENT OFFICE.

DOSSEY D. DANIEL, OF RICHMOND, VIRGINIA, ASSIGNOR OF ONE-HALF TO CHARLES B. HAYNES, OF RICHMOND, VIRGINIA.

ATTACHMENT FOR MOTION-PICTURE MACHINES.

1,168,607.

Specification of Letters Patent. Patented Jan. 18, 1916.

Application filed March 24, 1915. Serial No. 16,701.

To all whom it may concern:

Be it known that I, DOSSEY D. DANIEL, a citizen of the United States, residing at Richmond, in the county of Henrico and State of Virginia, have invented certain new and useful Improvements in Attachments for Motion-Picture Machines, of which the following is a specification, reference being had to the accompanying drawings.

This invention comprehends certain new and useful improvements in motion picture machines, and relates particularly to machines of the electric motor driven type.

The invention has for one of its principal objects improved means for making machines of this character entirely safe from the danger of fire, the parts being so constructed and arranged that immediately upon the stopping or breaking of the film the motor circuit will be automatically opened and the machine stopped.

A further object of the invention is an apparatus of this character which is capable of being easily applied to any of the conventional or other forms of motion picture machines, without altering the same in any way, and without detracting from the efficiency of the machine.

A still further object of the invention is an apparatus of this kind which will not only possess to a high degree the characteristics of safety, but it will also protect the film and serve to a large degree to prevent injury to the same as well as to preclude the possibility of the film piling up on the machine.

The invention has for another object, in an apparatus of this kind, an improved construction and arrangement of parts which will not only operate automatically to open the motor circuit upon the stopping or breaking of the film, but which will also at the same time shut off the light and simultaneously be capable of sounding an alarm or of performing other operations which will serve to instantly apprise the operator of the stopping of the machine by the shutting off of the current, and otherwise protecting the occupants of the theater or other place where the machine is installed. And the invention also aims to generally improve devices of this character so as to render them more safe, more economical in the use of the film, and more

generally desirable from a commercial standpoint.

With these and other objects in view, as will more fully appear as the description proceeds, the invention consists in certain constructions, arrangements and combinations of the parts that I shall hereinafter more fully describe and claim.

For a full understanding of the invention, reference is to be had to the following description and accompanying drawings, in which—

Figure 1 is a side elevation illustrating one application of my invention. Fig. 2 (Sheet 2) is a side elevation of the device. Fig. 3 is a sectional view on the line 3—3 of Fig. 2. Fig. 4 (Sheet 1) is a horizontal section on the line 4—4 of Fig. 3. Fig. 5 (Sheet 2) is a perspective view on a reduced scale, in the nature of a diagram.

Corresponding and like parts are referred to in the following description and designated in all of the views of the accompanying drawing by like reference characters.

Referring to the drawings, the numeral 1 designates the supporting frame or bracket of my improved apparatus, the same being of any desired construction, shape, size or design, just so long as it is capable of supporting and properly maintaining operating elements, the frame in the present invention being illustrated as embodying a base plate 2, a relatively short side or standard 3, and a relatively long or high side or standard 4, these parts being preferably integrally formed out of sheet metal or the like. Journaled in suitable bearings in the frame 1 are two transversely extending shafts 5 and 6 respectively, said shafts being mounted to turn or partially rotate about their longitudinal axes. Each of said shafts carries an arm, the arms being designated 5' and 6' respectively, and each of the arms carries a roller, the latter being designated 5" and 6" respectively.

In the present embodiment of the invention, the parts are so arranged that the roller 5" will be disposed within and in juxtaposition to the loop 7 of the film, which depends from the intermittent roller or element 8 of the film feeding apparatus and the draw roller 9 next in the series, and the roller 6" is disposed underneath and in contact with the film as it passes from the roller 9 down into the magazine 10.

The purpose of these rollers will be herein-after more fully described.

Cams 11 and 12 are mounted upon the shafts 5 and 6 on the end opposite the arms 5' and 6' and preferably on the outer face of the relatively long standard 4, said cams being disposed in contact with rocker arms 13 and 14 that are pivotally mounted intermediate of their ends on the outer side 10 of said standard. The arms 13 and 14 are operatively connected together in any desired way, as for example, by forming one of these arms with a recess 15 which receives the adjoining end 16 of the other arm, 15 whereby the bars will work simultaneously for their required purpose upon the operative movement of either of the two cams above referred to. 17 designates a trip arm, this arm in the present instance being pivotally connected at its lower end, as at 18, 20 to the arm 14 and extending upwardly therefrom on the outer side of the standard 4, said trip arm 17 being mounted for a reciprocating movement in a vertical direction and being preferably guided near its 25 upper end in a strap 19 or the like. The upper extremity of the trip arm 17 is designed for engagement with a keeper 20 which, in the present instance, is in the 30 form of a plate adapted to be slipped over the switch arm 21 and secured thereto by a set screw, the keeper 20 being also formed with an opening 22 designed to receive the upper preferably beveled extremity of the 35 trip arm 17 when the keeper 20 protrudes through a transversely extending slot 23 formed in the standard 4 near the upper end of the latter, as clearly illustrated in the drawings.

40 The switch arm or lever 21 is fulcrumed at its lower end on the inner face of the standard 4, and a spring 24 exerts its tension upon the switch lever to swing it inwardly away from the adjoining face of the standard 4, whereby it will carry its contact bar 25 out of engagement with the contact plates 26 to which the motor leads 27 are connected. When the circuit is closed the bar 25 bridges the contacts 26 but when the 45 latch 17 is drawn downwardly out of the opening 22 in the keeper 20, the keeper is immediately released and the spring 24 is permitted to act to move the switch lever 21 to its inoperative position and open the 50 circuit. The movement of the switch lever in this direction is limited in any desired way as, for example, by a stop arm 28.

55 In the preferred embodiment of the apparatus, a shutter or shield 29 is carried by an arm 30 projecting from the switch lever 21, whereby when the latter moves to its inoperative position to open the circuit, this shield will be carried to a position to shut off the light.

60 65 Preferably, the shaft 6 is encircled by a

spring 31, the tension of which may be varied by a set collar 32, whereby this shaft will be positively and quickly actuated.

From the foregoing description in connection with the accompanying drawings, the 70 operation of my improved apparatus will be apparent. In the practical use of the device, should the film stop from any cause, it is obvious that the slack 7 will be instantly drawn out of the film and the latter will 75 engage the roller 5'' with comparatively great force and instantly swing the arm 5' in a direction to so turn the shaft 5 so that its cam 11 will rock the arms 13 and 14 and cause the same to pull down upon the trip arm 17, whereupon the upper end of said trip arm will be drawn out of the opening 22 in the keeper 20 and the switch lever 21 will be instantly and automatically moved to its outer inoperative position to open the 80 motor circuit and bring the machine to a standstill. If, again, the film breaks at any point whatever, it is obvious that just as soon as the broken portion reaches the roller 6'' the arm 6' will be moved in a direction 85 to turn the shaft 6 to cause the cam 12 to operate the arm 14, and in a corresponding manner draw the trip arm 17 downwardly to release the switch lever. Thus, it will be seen that these two operations are entirely 90 independent of each other. That is to say, neither of them will interfere with the other in any way, and no matter whether the film is stopped from any cause whatsoever or breaks, instantly the trip arm will be moved 95 downwardly and the switch lever released so as to open the motor circuit and bring the machine to a standstill.

100 It is to be understood that my invention is not limited to the precise construction and arrangements of the parts hereinbefore described and illustrated in the accompanying drawings, but that the shafts 5 and 6 may be reversed if desired, that is, either one may be used in correlation with the loop 7 and 105 the other with that portion of the film which extends down from the roller 9 into the magazine 10 and it is also to be understood that various other changes may be made in the construction, arrangements and proportions of the parts without departing from the 110 scope of the invention as defined in the appended claims.

115 Preferably the switch arm 21 is grounded to the frame 1 and is so arranged that when it is moved to a position to open the motor circuit, it will close an electrical circuit comprising leads 33, which may extend to an electric bell 34 to sound an alarm or to any other apparatus desired as, for example, electrical means for instantly lighting the room or for any other purpose which will tend to promote the safety of the device. It is, 120 of course, to be understood that one of the leads 33 is electrically connected to the arm 125 130

which limits the outward movement of the switch lever so that just as soon as the lever contacts with said arm or bell or similar electrical device the circuit is closed.

5 In order to restore the parts to working condition, I preferably employ a contractile spring 35 connected, for example, to the arm 14 at one end and at its other end to the standard 4, this spring operating in an evident manner.

From the foregoing, it will be seen that I have provided a very simple, durable and efficient apparatus for the purpose hereinbefore described, which will not only serve as 15 a safety appliance for the machine and protect the film as set forth at the outset of the specification, but which will also work to open the motor circuit if the take-up in the magazine or other portion of the film feeding apparatus should fail to work. No matter 20 what may happen to the film whereby it might be stopped or disrupted in any way, my apparatus will instantly operate to open the motor circuit and preferably also sound 25 the alarm or operate some other electrical appliance which will conduce to the safety of the room or other place where the machine embodying my invention is installed.

What is claimed, is:

30 1. The combination with a motor driven motion picture machine and the film thereof, of means for automatically opening the motor circuit upon the stopping or breaking of the film, said means comprising rollers arranged respectively near the slack portion 35 of the film and in contact with a taut portion thereof, a switch arm, means tending to move the switch arm to open circuit position, means for holding the switch arm in closed 40 circuit position, an operative connection between said rollers, and releasing means arranged to release said holding means upon the changing of the slack portion of the film to a taut portion and the breaking of 45 the film respectively, said releasing means being controlled by said rollers.

2. An attachment for motion picture machines comprising a support, independently movable shafts mounted therein, arms carried by the respective shafts and arranged respectively to be operated by the stopping or breaking of the film, a switch arm, means tending to move the switch arm to a position to open the circuit of the motor of the machine, a trip arm engageable with the switch arm to hold the same against such movement, and operative connections between said shafts and said trip arm.

3. An attachment for motion picture machines comprising a support, independently movable shafts mounted therein, arms carried by the respective shafts and arranged respectively to be operated by the stopping of the film and the breaking thereof, a switch arm, means tending to move the switch arm

to a position to open the circuit of the motor of the machine, a trip arm engageable with the switch arm to hold the same against such movement, arms pivotally mounted upon the support and arranged for simultaneous operation, a connection between one of said pivoted arms and the trip arm, and means carried by the respective shafts and engageable with said pivoted arms, for the purpose specified.

4. An attachment for motor driven motion picture machines, comprising a support, shafts journaled in said support, arms carried by the respective shafts and arranged in juxtaposition to the film of the machine, said arms being adapted to be moved upon the stopping or breaking of the film, arms pivotally mounted on said support and arranged for simultaneous operation, means carried by said shafts and engaging with the respective arms to move the same, a switch arm, means tending to move the switch arm to a position to open the circuit of the motor, a keeper carried by said switch arm, and a trip connected to one of the pivoted arms and engageable with said keeper to hold the switch arm in a position to maintain the circuit closed.

5. An attachment for motor driven motion picture machines, comprising a support, independently movable shafts mounted in said support and arranged to be turned by the stopping or breaking of the film, a switch arm, means tending to move the switch arm to a position to open the motor circuit, a keeper carried by said switch arm and provided with an opening extending therethrough, the support being formed with a slot through which the keeper is adapted to protrude, a trip arm movable longitudinally on the support and engageable in the opening of the keeper to hold the switch arm in a position to maintain the circuit closed, and operative connections between said trip arms and the shafts whereby upon the turning of either of the shafts the trip arm will be moved out of the opening in the keeper and permit the switch arm to open.

6. An attachment for motor driven motion picture machines, comprising a support, independently movable shafts mounted therein, one of said shafts being spring actuated, arms carried by the respective shafts, rollers carried by said arms and designed for contact with the film whereby the arms will be moved and the shafts turned upon the stopping or breaking of the film, a switch arm, means tending to move the switch arm to a position to open the motor circuit, a keeper carried by the switch arm and having an opening formed therein, the support being formed with a slot through which the keeper is adapted to protrude, a trip arm movable longitudinally on the sup-

port and engageable at one end in said opening to hold the switch arm in a position to maintain the circuit closed, arms pivotally mounted upon the support, one of 5 said arms being formed with a recess in one end, the adjoining end of the other arm being mounted in said recess whereby the movement of one of the pivoted arms will be accompanied by the movement of the 10 other one, the trip arm being pivotally connected to one of said pivoted arms, and means carried by the shafts for engagement with the respective pivoted arms, as and for the purpose set forth.

15 7. The combination with a motor driven motion picture machine and the film thereof, of a switch arm, means for automatically moving the switch arm to a position to open the motor circuit upon the stopping or 20 breaking of the film, and a shutter carried by said switch arm, for the purpose specified.

25 8. An attachment for motor driven motion picture machines including a switch arm controlling a motor circuit, means tending to normally move the switch arm to open circuit position, means adapted to hold the switch arm in closed circuit position against the action of the first mentioned 30 means, a movable member adapted to be disposed in juxtaposition to the slack portion of the film, a movable member adapted to engage with the taut portion of the film, and an operative mechanical connection between 35 the movable members and the holding means, whereby said movable members control the releasing of said holding means.

9. An attachment for motor driven motion picture machines including substantially 40 movable members mounted for actuation upon the stopping or breaking of the film, a switch arm controlling the motor circuit of the machine, means tending to normally

maintain the arm in open circuit position, a trip for holding the arm in closed circuit 45 position, and means operatively connecting the trip and the said independently movable members, whereby the movement of said movable members will release the trip.

10. An attachment for motor driven motion picture machines including independently movable members mounted for actuation upon the stopping or breaking of the film, a switch arm controlling the motor circuit of the machine, means tending to 50 normally maintain the arm in open circuit position, a shutter carried by and movable with the switch arm, said shutter being disposed to screen the switch arm when the arm is in open switch position and being disposed in inoperative position when the switch arm is in closed circuit position, a trip for holding the arm in closed circuit 55 position, and means operatively connecting the trip and the said independently movable members, whereby the movement of said movable members will release the trip.

11. The combination with a motor driven motion picture machine and the film thereof, of a switch arm controlling the motor circuit, means for automatically moving the switch arm to open circuit position upon the stopping or breaking of the film, and a shutter carried by and movable with said switch arm, said shutter being disposed in 70 position to screen the film when the switch arm is in open circuit position and being inoperative, with respect to the film when the switch arm is in closed circuit position.

In testimony whereof I hereunto affix my 80 signature in the presence of two witnesses.

DOSSEY D. DANIEL.
